INTERNAL COMBUSTION ENGINE

Filed April 2, 1927

UNITED STATES PATENT OFFICE

HAROLD CAMINEZ, OF FARMINGDALE, NEW YORK, ASSIGNOR TO FAIRCHILD-CAMINEZ ENGINE CORPORATION, OF NEW YORK, N. Y., A CORPORATION OF NEW YORK

INTERNAL-COMBUSTION ENGINE

Application filed April 2, 1927. Serial No. 180,498.

This invention relates to internal combustion engines and particularly to the valve actuating mechanism therefor.

One object of the invention is the provision of a support for the rocker arm of an internal combustion engine which will be simple and light in construction and which may efficiently support the rocker arm by means of which the valve of the engine is operated.

10 Another object of the invention is the provision of a novel connection between the rocker arm thrust rod and the end of the rocker arm, which may be adjusted in a convenient manner to permit adjustments of the valve timing.

15 A further object of the invention is the provision of a rocker arm support and a thrust rod connection to the rocker arm which may be lubricated in an efficient manner, the construction being such that the lubricant is retained adjacent the moving parts and prevented from being thrown off in the rapid oscillatory movements imparted to the rocker arm.

20 Still further objects and advantages of the invention will be apparent from the following description and from the attached drawings in which:

25 Fig. 1 is a side elevation showing part of an internal combustion engine embodying the present invention, parts thereof being shown in section;

Fig. 2 is an enlarged sectional view of the valve gear of the present invention; and

30 Fig. 3 is a section of the line 3—3 of Fig. 2 through the rocker arm supporting shaft.

Referring more particularly to the drawings by reference numerals in which corresponding numerals designate like parts in the various views, 10 designates generally the cylinder-head of an internal combustion engine 11 of any suitable construction. The cylinder-head is provided with the customary intake and exhaust valves one of which is shown at 12, having a valve head 13 seated in the cylinder-head and having a stem portion 14 extending outwardly through the head of the cylinder. The customary valve closing means as shown, comprises the two valve

ends against the spring abutment member 17 mounted on the cylinder-head and at their other ends against the spring retainer 18 which is suitably fastened as by means of the tapered collar to the outer end of the valve stem. The valve is thus maintained seated in its normal position by reason of the outward thrust imparted by the valve springs.

35 The valve is actuated by the rocker arm 25 which is mounted on an axis 26 on a rocker arm support 27 fixed to the cylinder-head. The outer end of the arm is connected to a valve actuating push-rod 28 which is attached at its other end to a thrust member 29 suitably mounted in the guide sleeve 30 and actuated in a radial direction by the cam 31 provided on the engine shaft 32. The invention is represented in the drawings as applied to a cam engine of the type set forth in my prior Patent No. 1,594,045, patented July 27, 1926, 40 altho it will be apparent that the invention is applicable to engines of other types.

45 The rocker arm support, as shown, comprises an integral sheet metal member constructed of a material such as iron or steel having some slight inherent flexibility. The lower surface 35 of the support extends in a substantially lateral direction from the cylinder-head to which it is attached by a pair of attaching bolts 36 which pass through two 50 openings provided in the end portion 37 which rests on the cylinder-head. A separate sheet metal member 38 conforms to the shape of the surface 35 and the end portion 37 of the support and is provided to furnish additional 55 strength to the support member adjacent its point of connection to the cylinder-head. Integrally provided upwardly extending side ears 39 form an integral part of the supporting member 27, and a depending extension 60 60 is integrally provided on the outer end of the support 27. The depending projection 40 is provided with an attaching hole 41 which received a pin 42 to which is attached the bifurcated end 43 of a turnbuckle socket 44. 65 The turnbuckle socket is provided with internal threads which receive the threads on the end of the rod 45, the other end of which is threaded in the second turnbuckle socket 46 which is fastened by means of a pin 47 to an 70 75 80 85 90 95 100

55 60 65 70 75 80 85 90 95 100

attaching lug 48, mounted at a point on the engine remote from the rocker arm support. The rod 45 may be rotated within the turnbuckle sockets 44 and 46 and the thread at one 5 end of the rod 45 is a right-hand thread while a left-hand thread is provided at its other end so that rotation of the rod will vary the positioning of the end of the rocker arm support which overhangs the cylinder. Suitable lock nuts 49 and 50 may be tightened in place against the ends of the turnbuckle sockets to definitely fix the rod 45 in its various 10 positions of adjustment. The rod 45 is so adjusted that it normally pulls downwardly 15 on the end of the rocker arm support and operates under tension in transmitting the outward thrust exerted on the rocker arm when the latter is caused to actuate the valve.

The two upwardly extending ears 39 on 20 the rocker arm support are provided with openings 60 which receive the bearing bushing 61. These bearing bushings receive the rocker arm shaft 62 on which the rocker arm 25 is oscillatably mounted, the rocker arm being guided in its oscillation between the two opposed bushings 61, it being understood that an individual rocker arm support is provided for each of the rocker arms of the various valves of the engine cylinder.

30 The rocker arm support axis 26 is spaced laterally a considerable distance away from the axis of the engine cylinder with which it cooperates. The tension rod 45 is attached to a point on the end of the rocker arm support which is not very far from the direction of thrust exerted on the rocker arm supporting shaft during the operation of the valve. As shown, the rocker arm shaft 26 is positioned so that the tension rod 45 which 35 is preferably steel, assumes the major portion of the thrust exerted on the rocker arm shaft and on the support bracket. The balance of the thrust exerted on the support or bracket is applied to the connection at the 40 end 37 of the rocker arm support and assumed by the cylinder-head which is preferably constructed of aluminum or similar material. The major portion of the thrust on the rocker arm support is therefore transmitted to the engine case through the steel 45 rod and a minor portion only is taken through the aluminum cylinder-head which, because of the material and the heat at which it operates, has uncertain strength. The rod connecting the rocker arm support to the cam case is placed as close to the rocker arm axis as practical to relieve the cylinder-head to a large extent from the forces applied to the support.

50 The rod 45 being normally under tension pulls downwardly on the rocker arm support, slightly flexing it adjacent the point of connection of the support to the cylinder-head, this being permitted by the flexibility of the 55 material and the comparatively flat shape of

the support at this point of flexure. A constant strain will thus be exerted on the connection pins 42 and 47 and on the threads at the ends of the tension rod 45 so that no play or loose movements will obtain during the rapid reciprocation of the valve actuating mechanism. The rocker arm support will thus be held firmly in position and objectional vibrational tendencies of the rocker arm support will be eliminated. At the same time the clearance between the rocker arm roller 63 and the end of the valve stem 14 may be prevented from exceeding some efficient clearance limit when the engine operates at different temperatures and when the 60 various parts of the engine have expanded or contracted. It will be noted that the axis of the rocker arm shaft is so spaced between the depending projection 40 and the point of support on the engine cylinder-head that when the engine cylinder itself expands at 65 high temperatures, and the point of attachment of the support to the cylinder-head is moved outwardly, the rocker arm axis is moved outwardly through a proportionately 70 smaller distance. The projection 40 is connected to a point comparatively close to the engine axis by means of the supporting tension rod 45 which is exposed to the air and maintained comparatively cool, so that this 75 end of the rocker arm support will be maintained at a comparatively definite position in regard to the engine. The rocker arm axis 26 will thus be moved outwardly and inwardly about its two end connections in 80 such a manner that the expansion or contraction of the engine cylinder will be compensated to some extent and the clearance 85 between the rocker arm and the valve stem may be kept from exceeding some safe and efficient dimension. The proportionate spacing of the rocker arm shaft 26 between the connection to the exposed thrust rod 28 and the point of engagement with the valve stem 145 somewhat resembles the proportionate spacing 90 in a direction at right-angles to the cylinder axis, of its distance from the two supporting ends of the rocker arm support so that the clearance between the roller 63 and the valve stem may be kept comparatively 95 constant at varying temperatures of the engine cylinders.

100 The end 70 of the rocker arm is provided with internal threads 71 in which the threaded seat member 72 is mounted. The external threads 73 of this seat member are engaged by a lock nut 74 for locking the member 72 in its proper position on the end of the rocker arm. At its lower end the seat member 72 is provided with a hexagonal end 75 by which 105 it may be rotated and adjusted within the threaded end of the rocker arm. The seat member 72 is hollow and a restriction 76 adjacent its lower end is so formed and curved as to provide a seat 77 which is en- 110

gaged by the correspondingly curved portions of the rounded end 78 of the actuating rod 28. The rounded end 78 is provided on a short stem 79 which is welded or otherwise rigidly attached within the end of the hollow thrust or actuating rod 28. Within the hollow seat member 72 is a separate ball seat 80 of such size that it may be readily inserted in place through the upper end of the seat member and so formed that it fits the upper end of the ball 78 on the thrust rod. This seat member 80 is held in its proper position providing a bearing surface for the end of the ball 78 by means of the retaining plug 81 which has external threads engaging corresponding internal threads provided in the opening in the seat member 72. A slot 82 in the end of this plug 81 permits the adjustment of the plug and the adjacent seat 80 to their proper positions. It will be understood that the stem 79 of the actuating rod 28, being of smaller size than the restriction 76 of the seat member permits the insertion of the stem through the larger end opening in the seat member 72 and after being so inserted the end of the thrust rod 28 is then welded or otherwise fastened firmly to the stem 79. The connection provided between the rocker arm and the push-rod may be easily adjusted to compensate for wear or lost motion and permits quick and convenient assembly or removal of the parts, and adjustments of the valve clearance.

The threaded plug 81 at the outer side of the ball connection 78 and the engaging interfitting surfaces of the restriction 76 and the ball 78 prevents the loss of lubricant which is supplied to the moving parts of the connection just described. The lubricant is thus retained in the small space or chamber provided therefor as indicated at 85 and is supplied to this chamber through a series of small holes 86 extending laterally through the seat member 72. These holes 86 communicate with an annular space 87 provided in an intermediate portion of the seat member 72 as by cutting away the threads on the seat member adjacent this position. The rocker arm is provided with an oil or lubricant passage 88 which extends from the annular space 87 to the bearing connection between the rocker arm and the shaft 62 on which it is mounted. The shaft 62 is provided with an axial lubricant passage 89 which communicates with a transverse hole 90 through the shaft so that lubricant may be supplied through a pressure nipple or connection 91 mounted at one end of the shaft 62 for the supply of lubricant through the passages 89 and 90 to lubricate the bearing surfaces between the shaft 62 and the rocker arm, and also supply lubricant through the connecting passage 88, chamber 87 and holes 86 to the moving parts of the ball joint connection at the end of the rocker

arm. By reason of the lubricant passages and the arrangement just mentioned the moving parts of the valve mechanism may be properly lubricated and the construction is such that the lubricant itself will not be lost or thrown off during the rapid oscillatory movements of the valve gear. The lubricant may be supplied in a convenient manner to a stationary part of the valve gear even when the engine is in operation and the rocker arm and other actuating parts are in rapid movement.

The lower end of the thrust rod 28 is attached rigidly to the stem 95 at the end of which is a ball member 96 similar to the connection provided at the upper end of the thrust rod. The ball 96 engages a seat 97 which is provided at the outer end of the actuating plunger 29 which is reciprocated back and forth by the valve cam 31.

It will be understood that the construction described and shown with reference to one of the valves and valve actuating mechanism of the engine cylinder may be duplicated in a similar manner for the other valve or valves of the cylinder and that all of the engine cylinders may be constructed in a like manner.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In an internal combustion engine, a cylinder-head, a valve rocker arm, a rocker arm support tightly secured at one end to the cylinder head and overhanging said cylinder-head and comprising a sheet of metal part having some flexibility in a direction parallel to the axis of the cylinder at points just outside the place of attachment of the said support to the cylinder head, actuating means for said rocker arm, and a rigid brace connecting the outer end of said support to a remote point on the engine.
2. In an internal combustion engine, a cylinder-head, a valve rocker arm, a rocker arm support fixed to said cylinder-head for supporting said rocker arm on an axis overhanging said cylinder-head, and comprising a sheet of metal having some flexibility in a direct parallel to the axis of the cylinder at points just outside the place of attachment of the said support to the cylinder head and having upwardly extending bearing ears for said rocker arm, actuating means connected to one end of said arm for actuating the same, and a brace connecting the outer end of said support to a remote point on the engine and located in spaced relation to said actuating means.

3. In an internal combustion engine, a cylinder-head, a valve rocker arm, a rocker arm support fixed to and overhanging said cylinder-head for supporting said rocker arm and comprising a sheet of metal having some slight inherent flexibility and provided with integral upwardly extending bearing ears for said rocker arm, actuating means connected to one end of said rocker arm, and a tensioning brace connecting the outer end of said support to a point on the engine located inwardly from the cylinder-head, and means for adjusting the normal tension in said tensioning brace.
4. In an internal combustion engine, a cylinder-head, a valve rocker arm, a rocker arm support fixed to said cylinder-head at one end thereof and having some slight inherent flexibility in a direction substantially parallel to the cylinder axis, a tension rod fixed at one end to an outer portion of said support and at its other end to a remote part of the engine and normally pulling down upon the outer portion of said support, said support having side members extending outwardly therefrom, a shaft mounted in said side members and oscillatably supporting said rocker arm on an axis so located that the tension rod assumes the major part of the thrust exerted on said shaft, a thrust rod engaging one end of said rocker arm for oscillating said arm, and means for adjusting the tension of said tension rod.
5. A valve rocker arm support comprising an integral sheet metal member having bent up side ears integrally provided thereon forming rocker arm bearings between which a single rocker arm is adapted to be mounted, said member having attaching means at one end thereof by which it may be fixedly attached to an engine cylinder-head, and a depending projection integrally provided at the opposite end of said support and having an attaching means therein adapting it to be connected to a support.
6. A valve rocker arm support for internal combustion engines comprising a metal member having side ears providing a support for a rocker arm shaft, said support having a laterally extending lower surface one end of which may be rigidly attached to an engine cylinder-head, and an end extension on said support adapted to be connected to a supporting member, said support having a portion between the said ears and the said one end which is of small overall thickness so that flexing of the support is permitted at said portion.

In testimony whereof I hereto affix my signature.

HAROLD CAMINEZ.
